United States Patent Office

Des. 226,998
Patented May 29, 1973

226,998

CHAIR

Eugene J. Costabile, Oak Lawn, Ill., assignor to Mohasco
Industries, Inc., Amsterdam, N.Y.

Filed Apr. 22, 1971, Ser. No. 136,639

Term of patent 14 years

Int. Cl. D6—02

U.S. Cl. D6—71

FIG. 1

FIG. 2

FIG. 1 is a front perspective view of a chair showing my design; and

FIG. 2 is a side perspective view thereof.

The back of the chair is conventionally plain while the side not shown is substantially identical to the side shown.

I claim:

The ornamental design for a chair, as shown and described.
